FILTER BODY HEAD

Walter J. Kudlaty, Elmhurst, Ill., assignor to Marvel Engineering Company, Skokie, Ill., a corporation of Illinois

Filed Dec. 16, 1963, Ser. No. 77,822

Term of patent 14 years

(Ct. D46—1)

I claim:

The ornamental design for a filter body head, as shown and described.
